W. J. GOLDSWORTHY

GOLF PRACTICE BALL

Filed Dec. 27, 1923

INVENTOR

William J. Goldsworthy

UNITED STATES PATENT OFFICE.

WILLIAM J. GOLDSWORTHY, OF SAN FRANCISCO, CALIFORNIA.

GOLF PRACTICE BALL.

Application filed December 27, 1923. Serial No. 682,874.

To all whom it may concern:

Be it known that I, WILLIAM J. GOLDSWORTHY, a citizen of the United States, residing in the city and county of San Francisco, State of California, have invented a new and useful Improvement in Golf Practice Balls, of which the following is a specification.

The present invention relates generally to improvements in golf practicing and training devices wherewith a player may, while away from the golf course, practice and train in parts of the game and, from such practice and training, acquire greater proficiency in playing of an actual game of golf upon the golf course.

The invention relates particularly to a golf practice ball where the face of the club, used in hitting the ball, is provided with a puncturing pin and may be so claimed. Such puncturing pins for golf clubs have already been proposed and described reference being also made to a form described in my co-pending application Serial Number 25 679331.

In a practice game of golf it is always most advantageous and desirable that the practicing be done with an actual golf ball, or with a substitute for a golf ball, simulating closely in shape, size and appearance an actual golf ball so that the eye, both in the practice or in the actual game, will have, to all appearances, the same object before it.

Further desirable advantages, in a golf practice game, are to have such a ball register the accuracy with which the practice blows are made and also to be quickly recoverable after the blow has been made in order that the ball may be put again into play.

An object of the invention, where a puncturing pin is carried on the face of the club hitting the ball, is to provide a ball indicating the accuracy of the blows.

Another object of the invention, where a barbed puncturing pin is carried on the face of the club hitting the ball, is to provide a ball retrievable by the club during a part of the blow.

In attaining the objects named, other advantages pertaining to a golf practice ball, will appear as the nature of the invention is better understood.

In the accompanying drawings, wherein like numerals designate the same parts throughout the different views.

Figure 1 is a front elevation of the ball; Figure 2 is a cross section on line *x-y* of Figure 1;

Figures 3 and 4 are reproductions of Figure 2, showing enlargements of an interior hollow.

Figure 5 is one form of a puncturing pin secured to the striking face of an iron golf club on a reduced scale. Though not a part of the present invention, Figure 5 is inserted as an aid towards a better understanding of the invention. In the Figure 5 a side view is had of a puncturing pin 12 provided with a pivoted barb 13 and a cross section view is had of a club head 14, the head 15 of the puncturing pin 12 and a sheet member 16 overlapping and securing the pin head 15 to the striking face of the club 14.

In carrying the invention into effect a ball 5 of a spherical outline is provided whose exterior surface simulates in size and appearance an actual golf ball. The ball 5 may be made from any suitable material tending to lend it a desirable lightness of weight. The ball 5 may be constructed solidly throughout of light weight material such as unspun cotton, sponge rubber, etc., or the ball 5 may be of a hollow construction centrally. Rubber, celluloid, etc., will lend themselves to such a hollow construction, the desired lightness of the ball being always kept in view.

A sheet member 6 of uniform thickness, hereinafter called the blow receiving part 6, shown herein of circular outline, is provided. The blow receiving part 6 may be made from any suitable easily perforable sheet material such as paper or the like. The blow receiving part 6 is intended to contact with and extend over a portion of the surface of the ball 5, and be secured to the surface of the ball 5.

The blow receiving part 6, when secured upon the ball 5, is proposed to serve as a puncture receiver and indicator against which the face of the club hitting the ball will impact and by which the ball will be protected from damage by the club and the puncturing pin carried thereon and before referred to.

The simplest shape into which the blow receiving part 6 could be formed would be a flat shape, that is extended in a horizontal plane, and in that shape could be applied 5 to the surface of the ball 5 and be forced against the surface and made to assume the spherical shape of the surface against which it contacts. The edges of the circular shaped blow receiving part 6 would, in that 10 case, be caused to crease or overflow forming wrinkles or ridges at and on the circular edge of the blow receiving part 6 destroying thereby a desired superficial smoothness. An improvement in shape has been devised 15 whose advantages will be apparent. An alternate shape for the blow receiving part 6 is proposed in the shaping, in advance and before its application on the ball 5, of the blow receiving part 6 into a substantial segment 20 of a hollow sphere, where the plane, cutting the sphere, passes through the hollow of the sphere. Or in other words, the blow receiving part 6 is proposed to consist of a sheet of substantially uniform thickness 25 so shaped that one face, intended for the exterior or exposed face, will be convex or vaulted and the opposite face, intended for the interior or contacting face, will be concave or incurred with its lines paralleling 30 the exterior face. Such a shape, briefly and broadly described, could be called a saucer shape construction. The precurving or the preshaping of the blow receiving part 35 6 may be obtained by pressure. The blow receiving part 6 is intended to be of such weight and texture that the desired saucer shape could be made by pressure and the saucer shape retained by the blow receiving part 6 after the pressure has been removed. 40 The concaved or incurred contacting face of the saucer shaped blow receiving part 6 will be shaped to follow the lines of, and to fit snugly to, the surface of the ball 5 and it follows that the convex exterior exposed 45 face of the saucer shaped blow receiving part 6 will follow lines parallel to but outside the surface of the ball 5, thereby obtaining, when the saucer shaped blow receiving part 6 is secured to the ball 5, a 50 smoothness not obtained when the blow receiving part 6 is formed in the flat shape.

One means for securing the blow receiving part 6 to the ball 5, and though set forth 55 it is intended to be illustrative and not limiting, is by the use of an adhesive first applied to the contacting face, or parts of the contacting face, of the blow receiving part 6 and then the blow receiving part 6 brought 60 into contact with the surface of the ball 5 and secured to the surface of the ball 5 by the adhesive. The adhesive may be applied to the contacting face of the blow receiving part 6 in the moistened state and then the 65 part at once pressed on the surface of the ball 5 and the adhesive allowed to sufficient-

ly dry under the pressure to retain the blow receiving part 6 on the ball 5, or the adhesive may be applied to the contacting face of the blow receiving part 6 in the moistened state and then dried thereon and at a later time 70 again moistened and at that time the part pressed on the ball 5 and the adhesive allowed to dry sufficiently under the pressure to retain the blow receiving part 6 on the ball 5. 75

It is intended that the blow receiving part 6 may be removed from the ball 5 when beyond further use and be replaced by a fresh unused blow receiving part 6. An easy 80 way for removing the blow receiving part 6 from the ball 5 would be by soaking in water until the adhesive yields and allows the blow receiving part 6 to be removed from the ball 5.

On the opposite exterior exposed face of the blow receiving part 6, hereinafter called the exposed face of the blow receiving part 6, a target like figure 7 is provided located centrally of the blow receiving part 6. The target like figure 7 is made to possess a regularity of outline, shown in this case of a regular circular outline. Associated with the outline of the target like figure 7 is a provided break in its mentioned regularity 90 of outline. 95

The associated break in the regular outline of the target like figure 7 may consist of an indentation in such outline or a projection from such outline, in either case, sufficient to make a point on the regular outline of the target like figure 7 appreciable to the eye and whereby the blow receiving part 6 may be positioned. The preferred form of such a break in the regular outline 100 of the target like figure 7 is shown by the projection 8 in association therewith and extending therefrom. The associated figure 8 may be formed contacting with the outline of the target like figure 7 or at a 105 distance therefrom and the purpose of the association of the two figures 7 and 8, as above stated, maintained. In whatever way the two figures 7 and 8 may be associated, the further purpose will be secured of having provided on the exposed face of the blow receiving part 6 two essential points, namely the figures 7 and 8, wherefrom any subsequent marks made on the blow receiving part 6, to wit, marks made by the puncturing pin carried by the club hitting the blow receiving part 6, may be computed. The described figures 7 and 8 may consist of the impressed inked figures of the printing art or may consist of depressions or expressions formed in any manner in or on the exposed face of the blow receiving part 6 with sufficient distinctness to be readily discernible to the eye. 115

The thickness of the blow receiving part 6 will enter into and be a factor in the 120 125 130

construction of the ball 5. For the blow receiving part 6 may be provided of a thickness such that the puncturing pin, carried on the face of the club hitting the exposed 5 face of the blow receiving part 6, if of a length less than the thickness of the blow receiving part 6, will bury its length in the blow receiving part 6 without penetrating the ball 5. When, however, a puncturing pin, carried on the face of the club hitting the blow receiving part 6, is of a length greater than the thickness of the blow receiving part 6, it is plain that the point of the puncturing pin will penetrate entirely 10 through and beyond the blow receiving part 6 and enter the surface of the ball 5. Where the ball 5 is of either solid or hollow construction internally, the continued entering of the puncturing pin into the surface of the ball 5, as the successive worn blow receiving parts 6 are removed and replaced by fresh blow receiving parts 6, will tend to deface and eventually ruin for use the ball 5. To obviate this and also to provide a 15 space interiorly of the ball 5 for parts of the puncturing pin to function, where the ball 5 is of solid construction interiorly, a section of the surface and interior body of the ball 5 is hollowed out forming a depression 9 extending interiorly and towards the center of the ball 5. The hollowed out section 9 of the ball 5 again may be extended to include or go beyond the center of the ball 5 and, in the last case, a virtually 20 hollow ball 5 be formed with an opening in the wall thereof affording free and uninterrupted passage from the space exteriorly of the ball 5 into the interior hollow 9 of the ball 5. Or the ball 5 may first be formed 25 with an interior hollow 9, of a greater or lesser extent as desired, and then a portion of the encompassing wall of the ball 5 removed, forming a free and open communication between the interior hollow 9 of the ball 5 and the free space surrounding the 30 surface of the ball 5.

The variations in the shape of the interiorly extending depression or hollow 9 of the ball 5 would follow the choice of material 35 from which the ball 5 is constructed. Across the said opening in and through the surface of the ball 5, affording a free communication between the interiorly extending depression or hollow 9 and the free space surrounding the ball 5, the already described blow receiving part 6 is made to bridge and overlap the opening and be secured, by the adhesive method before described or otherwise, to the surface of the ball 5 by those 40 parts of its contacting face overlapping on to the surface of the ball 5 beyond the rim of the opening.

The device with its parts constructed and assembled as described, and used in practice 45 where the club used carries on its face a

puncturing pin, will be placed upon the ground played upon, and the face of the club with attached puncturing pin advanced to the ball, as usual in golf in the addressing 50 of a ball before making a blow. During such address the bottom of the club will be flat upon the ground with the puncturing pin in touch with the blow receiving part 6, preferably at the center of the target 55 like figure 7, and the position of the associated figure 8 relative to the ground played upon will be noted by the player. It is evident that, in the blow succeeding the described address, the accuracy of the blow 60 will be indicated on the blow receiving part 6 by the puncture made therein by the puncturing pin, that is if the blow has been made fairly and in the center. Or if delivered off center, whether the device has been topped, 65 scuffed, heeled or toed, the reading being made from the position of the puncture, just made in the blow receiver 6, relative to the associated figures 7 and 8 and their positions before the blow was delivered. A 70 barb arrangement 13, preferably pivoted near the point of the pin 12 as shown in the Figure 5, and more fully described in my co-pending application before mentioned, when carried entirely through and beyond the 75 blow receiving part 6 into the interior depression or hollow 9 of the ball 5 by the puncturing pin 12, will act to keep the device from flying away from the club and the club itself will retrieve the device at the finish 80 of the blow. After such retrieving of the device, the puncturing pin and barb may be withdrawn through the blow receiving part 6, or the blow receiving part 6 may be torn from the ball 5 and replace by a fresh 85 unused blow receiving part 6.

In fashioning the foregoing described construction of the hollow ball 5, provided with an opening through the wall thereof affording a free passage through the surface of the hollow ball 5 into its interior hollow 9, it 90 has been found, where the material out of which the wall of such a hollow ball 5 is made possesses a resilient quality, that the blow receiving part 6 may be secured to the hollow ball 5 without the aid of an adhesive. For, where the wall of the hollow ball 5 collapses or gives in under pressure and returns to its normal shape when the pressure is 95 removed, it is evident during such collapsing or giving in of the wall, that a part of the air interiorly of the hollow ball 5, will be expelled through the opening in the wall of the hollow ball 5. If the blow receiving part 6, as described, is then placed over and 100 closes the opening, while the pressure on the wall of the hollow ball 5 is maintained, it is evident that the blow receiving part 6 will be held to and over the opening and be retained on the hollow ball 5 by the force 105 of the pressure which will be established by 110

the air exteriorly of the hollow ball 5 acting on the blow receiving part 6. Thus a suction method, instead of an adhesive method already described but stated as not being limited thereto, for securing the blow receiving part 6 to the surface of the hollow ball 5 is supplied without any change in the construction of the parts used as heretofore described.

10. If desired in the way of practice, a hollow ball 5 with an opening covered by the blow receiving parts 6 may have other blow receiving parts 6 secured to its surface at points where no opening is provided in the 15 surface as shown in the drawing. This would be desirable where a number of clubs, with a different form of pin on each club, is intended to be used.

Having described the invention in language 20 intended to be illustrative and not limiting, mention is made of the fact that, modification may be made in the form, design, construction, connections or in other particulars concerning the parts shown and described without departing from the spirit 25 and scope of the invention as set forth in the following claims.

What I claim as new and desire to secure by Letters Patent, is—

30. 1. In a golf practice ball, in combination, a ball, a hollow removed section of the structure of the ball extending inwardly of the ball and including a portion of the surface of the ball, a perforable sheet member bridging and overlapping the said hollow and a means holding the said perforable sheet member to the ball.

40. 2. In a golf practice ball, in combination, a substantially hollow ball, an opening formed through the wall thereof affording a free communication between the interior hollow of the ball and the free space exteriorly of the ball and a perforable sheet member bridging the said opening and secured to the surface of the ball.

45. 3. In a golf practice ball, in combination, a ball, a hollow formed interiorly of the ball, an opening in the surface of the ball connecting with the said interior hollow, a perforable sheet member bridging the said opening and secured by one face to the ball and impressed figures on the opposite face of the said perforable sheet member constituting a target thereon.

55. 4. In a golf practice ball, in combination, a substantially hollow ball the wall of which possesses a resilient quality, an opening in the surface of the ball extending through the said wall and connecting with the interior hollow, through which opening the air interiorly of the ball is expelled by external pressure on the said resilient wall, and a perforable sheet member bridging the said opening and held on the ball by the air attempting to enter the said opening upon the

cessation of the said external pressure on the said resilient wall of the ball.

5. In a golf practice ball, in combination, a substantially hollow ball the wall of which possesses a resilient quality, an opening in the surface of the ball extending through the said wall and connecting with the interior hollow, through which opening the air interiorly of the ball is expelled by external pressure on the said resilient wall, a perforable sheet member bridging the said opening and held with one face against the ball by the air attempting to enter the said opening upon the cessation of the said external pressure and impressions formed on the opposite free face of the said perforable sheet member constituting a target thereon.

6. In a golf practice ball, in combination, a ball, a hollow formed interiorly of the ball, an opening in the surface of ball connecting with the said interior hollow and a perforable sheet member bridging and overlapping the said opening and secured to the ball by an adhesive.

7. In a golf practice ball, in combination, 90 a ball, a perforable member of a substantially uniform thickness formed into a concavo-convex shape and adapted to cover a portion of the surface of the ball and to contact, by its concave face, closely to the 95 surface of the ball, a means securing the concavo-convex shaped member to the ball and impressions formed on the convex face thereof constituting a target thereon.

8. In a golf practice ball, in combination, 100 a ball, a hollow formed interiorly of the ball, an opening in the surface of the ball connecting with the said interior hollow, a concavo-convex shaped perforable member of a substantially uniform thickness bridging and overlapping the said opening and secured to the ball.

9. In a golf practice ball, in combination, 110 a ball, a hollow formed interiorly of the ball, an opening in the surface of the ball connecting with the said interior hollow, a concavo-convex shaped perforable member of a substantially uniform thickness bridging and overlapping, by its concave face, 115 the said opening and secured to the ball by the overlapping part of its concave face and impressions formed on its convex face constituting a target thereon.

10. In a golf practice ball, in combination, 120 a ball, a hollow formed interiorly of the ball, an opening in the surface of the ball connecting with the said interior hollow, a perforable sheet member of a concavo-convex shape bridging and overlapping, with 125 its concave face, the said opening, an adhesive securing the said overlapping parts to the surface of the ball and an impression of uniform outline formed on the convex face of the said perforable sheet member centrally thereof with an interruption in the 130

said uniformity of outline at one point thereon.

11. In a golf practice ball, for receiving a puncturing pin carried on the hitting face 5 of the club striking the ball, in combination, a ball, a puncturable sheet member covering a portion of the surface of the ball and secured by one of its faces to the ball, and impressions formed on the opposite free face 10 thereof constituting a target thereon.

12. In a golf practice ball for receiving a puncturing pin carried on the striking face of the club hitting the ball, in combination, a ball, a puncturable sheet member covering 15 a portion of the surface of the ball, an adhesive securing the said puncturable sheet member by one of its faces to the ball and an impression of regular outline formed centrally on the opposite free face with an 20 interruption in the said regularity of outline at one point thereof.

13. In a golf practice ball for receiving a puncturing pin carried on the striking face of the club hitting the ball, in combination, 25 a hollow ball, a puncturable sheet member, covering a portion of the surface of the ball and secured by one of its faces thereto and impressions formed on the opposite free face thereof constituting a target 30 thereon.

14. In a golf practice ball for receiving a puncturing pin carried on the hitting face of the club striking the ball, in combination, a hollow ball, a puncturable sheet member 35 covering a portion of the surface of the ball, an adhesive securing the said puncturable sheet member by one of its faces to the ball and an impression of regular outline formed centrally of the opposite free face thereof 40 with an interruption in the said regularity of outline at one point thereof.

15. An article of manufacture, in combination, a sheet of perforable material, adapted to cover a portion of the surface of 45 a practice golf ball, an adhesive applied to one face thereof for securing the said sheet to the ball and an impression of a regular outline formed centrally of the opposite face thereof with an interruption in the 50 said regularity of outline at one point thereon.

16. An article of manufacture, in combination, a concavo-convex shaped perforable member of a substantially uniform thickness, adapted to contact with and cover 55 by its concave face a portion of the surface of a practice golf ball and impressions

formed on the convex face thereof constituting a target thereon.

17. An article of manufacture, in combination, a concavo-convex shaped perforable member of a substantially uniform thickness, adapted to contact with and cover, by its concave face, a portion of the surface of a practice golf ball, an adhesive 60 provided on the said concave face, adapted to secure the same to a ball, and impressions formed on the convex face constituting a target thereon.

18. An article of manufacture, in combination, a concavo-convex shaped perforable member of a substantially uniform thickness, adapted to contact with and cover, by its concave face, a portion of the surface of a practice golf ball, an adhesive 65 provided on the said concave face, adapted to secure the same to a ball, and an impression 70 of a regular outline formed centrally of the convex face with an interruption in the said regularity of said outline at one 75 point thereon.

19. In a golf practice ball, in combination, a substantially hollow ball the wall of which possesses a resilient quality, an opening in the surface of the ball, extending 80 through the said wall and connecting with the interior hollow, through which opening the air interiorly of the ball is expelled by 85 external pressure on the said resilient wall, a concavo-convex shaped perforable member 90 bridging and overlapping the said opening and held on the ball by the air attempting to enter the said opening upon the cessation of the said external pressure on the said resilient wall of the ball.

20. In a golf practice ball, in combination, a substantially hollow ball the wall of which possesses a resilient quality, an opening in the surface of the ball extending 95 through the said wall and connecting with the interior hollow, through which opening the air interiorly of the ball is expelled by 100 external pressure on the said resilient wall, a concavo-convex shaped perforable member 105 bridging and overlapping the said opening and held, by the concave face, to the ball by the air attempting to enter the said opening upon the cessation of the said external pressure upon the said resilient wall of the ball and impressions formed on the 110 convex face of the said perforable member constituting a target thereon.

December 22nd, 1923.

WILLIAM J. GOLDSWORTHY.
